UNITED STATES PATENT OFFICE.

LOUIS G. PACENT, OF WINFIELD, NEW YORK, ASSIGNEE TO PACENT ELECTRIC COMPANY, INC., OF NEW YORK, N. Y., A CORPORATION OF NEW YORK.

SPRING JACK.

Application filed April 17, 1923. Serial No. 632,597.

This invention relates to spring jacks of the telephone type, and is directed, more particularly, to an improved self-contained multiple jack structure intended more especially for use in conjunction with radio apparatus.

The invention has for its object the provision of a simple, compact and inexpensive multiple jack structure which can be readily mounted on the panel of a radio transmitting or receiving set, or in fact on any flat surface, and which is particularly designed to facilitate plugging in one or more telephone receiving sets.

The device constituting the preferred embodiment of this invention comprises a molded base of insulating material, such as hard rubber, having a recess on the side which is intended to be mounted against the panel. This recess is designed to receive a plurality of sets of jack springs, and the base is provided with a plurality of apertures of suitable size to permit the insertion therethrough of ordinary connecting plugs of the telephone type into engagement with the jack springs. These apertures correspond in number with the sets of jack springs, and each is arranged opposite one of the sets of jack springs. Generally, the jack springs are arranged so that when a plurality of telephone headsets are plugged in, the receivers are all connected in series.

Multi-jacks in accordance with this invention are usually designed to accommodate three plugs, but, of course, they may be designed to accommodate any desired number.

A very advantageous feature of the preferred embodiment of this invention resides in the fact that it is so designed that when it is mounted on the face of a vertical panel the center lines of the jacks are disposed at a convenient angle to the face of the panel. This makes it especially convenient for plugging in and reduces by a considerable amount the distance which the multi-jack would otherwise project beyond the base of the panel, thus contributing materially to the appearance of the device without detracting in the least from its utility and convenience.

For a detailed description of the preferred embodiment of the invention reference will now be made to the accompanying drawing, in which—

Fig. 1 is a perspective view of the preferred embodiment of the invention;

Fig. 2 is a cross-sectional view of the multi-jack shown in perspective in Fig. 1; and

Fig. 3 is a view of the rear of the multi-jack, that is, of the side which goes next the panel.

The perspective view, Fig. 1, shows very clearly the shape of the base 1, which may be molded of any suitable insulating material. This base is provided with a large recess 2, which is substantially enclosed when it is mounted on a panel or other flat surface, as the case may be. The base 1 has a substantially trapeziform cross section, as is clearly shown in Fig. 2, this arrangement facilitating the disposition of the apertures 3, so that the plugs 4 can be inserted at a convenient angle to the plane of the panel 5 on which the device is mounted. It will be readily understood that the apertures 3 are of such size as to permit easy insertion of a connecting plug 4, which is designed to engage the jack springs. Within the recess 2 and secured to the base 1 are a plurality of sets of jack springs 6. These comprise the substantially U-shaped intermediate springs 6^a and the end springs 6^b. The latter are secured to the binding posts 7, while the former are secured to the base by means of screws 8. When no plugs are inserted in the device, the jack springs constituting each set make contact with each other and, as will be clear from Fig. 3, the binding posts 7 are connected together through the jack springs.

If, for instance, a plug 4 connected with a telephone headset, which is not shown, is plugged into any one of the apertures 3 and into engagement with the corresponding set of jack springs as shown in Fig. 3, the telephone headset will be connected across the binding posts 7. If, then, another plug having a second telephone headset connected with it is plugged into another one of the apertures 3 and into engagement with the corresponding set of jack springs, the two headsets will be connected across the binding posts 7 in series relation. Likewise, if a third headset is plugged in, the three will be connected in series relation across the binding posts 7.

From an examination of Fig. 2 it becomes apparent that if the device were so designed

that the center lines of the jacks were normal to the plane of the panel on which it is mounted, the base 1 would of necessity be considerably higher that is, the distance 5 which it would project from the face of the panel would, of necessity, be increased. On the other hand, if the base 1 were made rectangular and the jacks so arranged that their center lines were parallel to the face 10 of the panel, it would not be so convenient for the operator as the arrangement shown, and furthermore would also somewhat increase the height of the device, which, of course, is objectionable from the standpoint 15 of appearance, as well as economy in manufacture.

A still further advantage inherent in the form of base shown resides in the fact that it lends itself particularly well to the process 20 of molding as will be apparent.

Apertures 9 are provided in the base 1 for the mounting screws whereby the device may be attached to the panel, and grooves 25 10 are provided for bringing in the conductors which are connected to the binding posts 7.

It should be understood that the inven-

tion is not limited to the specific embodiment 30 illustrated and described, but only by the scope of the appended claim.

I claim:

A switching device comprising a base of insulating material adapted to be mounted on a panel, said base having a substantially trapeziform cross section and recessed on the side thereof which is intended to be placed against the panel, a plurality of sets of jack springs secured to said base and disposed within the recess therein, said base having a plurality of apertures having center lines 40 extending at an angle to the surface of the panel on which the base is adapted to be mounted, said apertures corresponding in number to the said sets of jack springs, each of said apertures being individually associated with one of said sets of jack springs and so disposed as to permit the insertion therethrough of a connecting plug whereby the plug can be operatively engaged with the respectively associated set of jack 50 springs.

In testimony whereof I affix my signature.

LOUIS G. PACENT.
